(57) **ABSTRACT**

Disclosed is a magnetic fluid speaker, including a housing, a control panel and loudspeaker assemblies, where the housing is provided with an accommodating cavity, the housing is further provided with windows, and the windows are configured for communicating the outside and the accommodating cavity; the control panel and the loudspeaker assemblies are both arranged in the accommodating cavity, where the loudspeaker assemblies are directly opposite to the windows, and the loudspeaker assemblies are electrically connected to the control panel; an electromagnetic device is arranged on each loudspeaker assembly, the electromagnetic device is electrically connected to the control panel, the electromagnetic devices are arranged on the loudspeaker assemblies, the magnetic fluid display devices are arranged in the windows, the magnetic fluid display device is exposed on the outer surface of the housing, and the magnetic fluid display device is located at the front side of the electromagnetic device.

1

MAGNETIC FLUID SPEAKER

TECHNICAL FIELD

The present disclosure relates to the technical field of audio products, and particularly relates to a magnetic fluid speaker.

BACKGROUND

With social progress, people yearn for a more colorful life. Song and dance, as an entertainment form that has been passed down for thousands of years, has been deeply rooted in the lives of people of all ethnic groups. However, with the development and progress of technology, people have raised increasing and more stringent requirements for the performance forms and venues of song and dance, audio systems have been continuously improved to meet people's needs, and audio products have been developed continuously and become very mature. In addition to professional audio products, existing audio products are usually combined with various existing equipment to exert a new role.

Currently, an audio product is mainly a bluetooth speaker, mainly including a housing, a control panel and loudspeaker assemblies, where the housing is provided with an accommodating cavity, sound holes are formed on the housing, and the sound holes are configured for communicating the outside and the accommodating cavity; the control panel and the loudspeaker assemblies are both arranged in the accommodating cavity, where the loudspeaker assemblies are directly opposite to the sound holes, and the loudspeaker assemblies are electrically connected to the control panel. However, this kind of audio product only plays a role of playing music, is relatively single in functions, and is incapable to meet sound visualization needs and facilitate users' pursuit of increasing diversity and personality. Therefore, it is necessary to improve the existing audio products.

SUMMARY

In view of this, aiming at the deficiencies in the prior art, a main objective of the present disclosure is to provide a magnetic fluid speaker that is capable to effectively solve the problem that existing audio products cannot meet sound visualization needs.

To achieve the above objective, the present disclosure adopts the following technical solution:

a magnetic fluid speaker, including a housing, a control panel and loudspeaker assemblies, where the housing is provided with an accommodating cavity, the housing is further provided with windows, and the windows are configured for communicating the outside and the accommodating cavity; the control panel and the loudspeaker assemblies are both arranged in the accommodating cavity, where the loudspeaker assemblies are directly opposite to the windows, and the loudspeaker assemblies are electrically connected to the control panel; and an electromagnetic device is arranged on each loudspeaker assembly, the electromagnetic device is electrically connected to the control panel, the magnetic fluid display devices are arranged in the windows, the magnetic fluid display device is exposed on the outer surface of the housing, and the magnetic fluid display device is located at the front side of the electromagnetic device.

Two windows are bilaterally arranged in a symmetrical manner, correspondingly, both two loudspeaker assemblies

2

and two magnetic fluid display devices are bilaterally arranged in a symmetrical manner, the two loudspeaker assemblies are directly opposite to the two windows respectively, and the two magnetic fluid display devices are respectively arranged in the two windows.

The housing includes a front housing, a rear cover, an end cover and an outer sleeve, where the front housing, the rear cover and the end cover are spliced and enclosed to form the accommodating cavity, the outer sleeve is sleeved outside the front housing and the rear cover, the outer sleeve is in clearance fit with the front housing, a plurality of sound holes are formed on the outer sleeve, the plurality of sound holes are communicated with the accommodating cavity, and the windows are located on the front housing and the outer sleeve.

Preferably, a radiator is arranged on the front housing.

Preferably, a storage battery is arranged in the accommodating cavity, and the storage battery is electrically connected to the control panel.

Preferably, the control panel is connected to a button panel, and the button panel is exposed on the housing.

Preferably, the magnetic fluid display device comprises a transparent box body and a magnetic fluid enclosed in the transparent box body.

Preferably, the transparent box body is made of glass or plastic.

Preferably, the transparent box body has a disc-shaped structure.

Preferably, the housing has a rectangular structure.

Compared with the prior art, the present disclosure has obvious advantages and beneficial effects, and specifically, it can be seen from the above technical solution that:

the electromagnetic devices are arranged on the loudspeaker assemblies, the magnetic fluid display devices are arranged in the windows, the magnetic fluid display device is exposed on the outer surface of the housing, and the magnetic fluid display device is located at the front side of the electromagnetic device, so that the electromagnetic device generates a changing magnetic field with changes in sound, thereby controlling the magnetic fluid display device, achieving sound visualization, and facilitating users' pursuit of increasing diversity and personality.

BRIEF DESCRIPTION OF THE DRAWINGS

FIG. 1 is a three-dimensional schematic diagram of assembly of a preferred embodiment of the present disclosure.

FIG. 2 is a three-dimensional schematic diagram of assembly of a preferred embodiment of the present disclosure from another perspective.

FIG. 3 is an exploded view of a preferred embodiment of the present disclosure.

FIG. 4 is an exploded view of a preferred embodiment of the present disclosure from another perspective.

FIG. 5 is a sectional view of a preferred embodiment of the present disclosure.

DESCRIPTION OF REFERENCE NUMERALS

10, housing; 11, front housing; 12, rear cover; 13, end cover; 14, outer sleeve; 15, radiator; 101, accommodating cavity; 102, window; 103, sound hole; 20, control panel; 30, loudspeaker assembly; 31, electromagnetic device; 40, mag-

netic fluid display device; **41**, transparent box body; **42**, magnetic fluid; **50**, storage battery; and **60**, button panel.

DETAILED DESCRIPTIONS OF THE EMBODIMENTS

With reference to FIGS. 1-5, a specific structure of the present disclosure in a preferred embodiment is shown, including a housing **10**, a control panel **20** and loudspeaker assemblies **30**.

The housing **10** is provided with an accommodating cavity **101**, and the housing **10** is further provided with windows **102**, where the windows **102** are configured for communicating the outside and the accommodating cavity **101**. Specifically, the housing **10** includes a front housing **11**, a rear cover **12**, an end cover **13** and an outer sleeve **14**, where the front housing **11**, the rear cover **12** and the end cover **13** are spliced and enclosed to form the accommodating cavity **101**, the outer sleeve **14** is sleeved outside the front housing **11** and the rear cover **12**, the outer sleeve **14** is in clearance fit with the front housing **11**, a plurality of sound holes **103** are formed on the outer sleeve **14**, the plurality of sound holes **103** are communicated with the accommodating cavity **101**, and the windows **102** are located on the front housing **11** and the outer sleeve **14** to facilitate outward sound transmission. In addition, a radiator **15** is arranged on the front housing **11** for better outward sound transmission. Further, the housing **10** has a rectangular structure, looking simple and beautiful in shape. Furthermore, two windows **102** are bilaterally arranged in a symmetrical manner.

The control panel **20** and the loudspeaker assemblies **30** are both arranged in the accommodating cavity **101**, where the loudspeaker assemblies **30** are directly opposite to the windows **102**, the loudspeaker assemblies **30** are electrically connected to the control panel **20**, an electromagnetic device **31** is arranged on each loudspeaker assembly **30**, and the electromagnetic device **31** is electrically connected to the control panel **20**.

A magnetic fluid display device **40** is arranged in each window **102**, the magnetic fluid display device **40** is exposed on an outer surface of the housing **10**, and the magnetic fluid display device **40** is located at a front side of the electromagnetic device **31**. In this embodiment, the magnetic fluid display device **40** includes a transparent box body **41** and a magnetic fluid **42** enclosed in the transparent box body **41**, where the transparent box body **41** is made of glass or plastic (no limitation on materials), and the transparent box body **41** has a disc-shaped structure (no limitation on shapes). The magnetic fluid **42** is composed of magnetic nanometer particles, a base solution and a surfactant, and has both fluidity of liquid and magnetism of magnetic solid materials. Further, both two loudspeaker assemblies **30** and two magnetic fluid display devices **40** are bilaterally arranged in a symmetrical manner, the two loudspeaker assemblies **30** are directly opposite to the two windows **102** respectively, and the two magnetic fluid display devices **40** are respectively arranged in the two windows **102**.

Furthermore, a storage battery **50** is arranged in the accommodating cavity **101**, and the storage battery **50** is electrically connected to the control panel **20** to provide power to the control panel **20**. In addition, the control panel **20** is connected to a button panel **60**, and the button panel **60** is exposed on the housing **10** to facilitates control.

A detailed working process of this embodiment is as follows:

During working, when an audio signal is transmitted to the loudspeaker assemblies **30** through the control panel **20**, the loudspeaker assemblies **30** play sound, at the same time, the control panel **20** analyzes the audio signal and generates an analog signal, and the analog signal is amplified and transmitted to an electromagnetic coil of the electromagnetic device **31** through a conversion circuit, so that the electromagnetic coil generates a magnetic field, then the magnetic field and the magnetic fluid **42** inside the transparent box body **41** cause magnetic field induction, and the originally static magnetic fluid **42** can immediately bounce once feeling energy, thus achieving sound visualization.

A design focus of the present disclosure is as follows: the electromagnetic devices are arranged on the loudspeaker assemblies, the magnetic fluid display devices are arranged in the windows, the magnetic fluid display device is exposed on the outer surface of the housing, and the magnetic fluid display device is located at the front side of the electromagnetic device, so that the electromagnetic device generates a changing magnetic field with changes in sound, thereby controlling the magnetic fluid display device, achieving sound visualization, and satisfying users' pursuit of increasing diversity and personality.

Technical principles of the present disclosure are described above with reference to specific embodiments. These descriptions are only intended to explain the principles of the present disclosure and cannot be interpreted, in any way, as limiting the protection scope of the present disclosure. Based on the explanation, other specific embodiments of the present disclosure can be contemplated by those skilled in the art without making creative efforts, and all these embodiments fall within the protection scope of the present disclosure.

What is claimed is:

1. A magnetic fluid speaker, comprising a housing, a control panel and loudspeaker assemblies, wherein the housing is provided with an accommodating cavity, the housing is further provided with windows, and the windows are configured for communicating the outside and the accommodating cavity; the control panel and the loudspeaker assemblies are both arranged in the accommodating cavity, where the loudspeaker assemblies are directly opposite to the windows, and the loudspeaker assemblies are electrically connected to the control panel; and an electromagnetic device is arranged on each loudspeaker assembly, the electromagnetic device is electrically connected to the control panel, the magnetic fluid display devices are arranged in the windows, the magnetic fluid display device is exposed on the outer surface of the housing, and the magnetic fluid display device is located at the front side of the electromagnetic device.

2. The magnetic fluid speaker according to claim 1, wherein two windows are bilaterally arranged in a symmetrical manner, correspondingly, both two loudspeaker assemblies and two magnetic fluid display devices are bilaterally arranged in a symmetrical manner, the two loudspeaker assemblies are directly opposite to the two windows respectively, and the two magnetic fluid display devices are respectively arranged in the two windows.

3. The magnetic fluid speaker according to claim 1, wherein the housing comprises a front housing, a rear cover, an end cover and an outer sleeve, wherein the front housing, the rear cover and the end cover are spliced and enclosed to form the accommodating cavity, the outer sleeve is sleeved outside the front housing and the rear cover, the outer sleeve is in clearance fit with the front housing, a plurality of sound

holes are formed on the outer sleeve, the plurality of sound holes are communicated with the accommodating cavity, and the windows are located on the front housing and the outer sleeve.

4. The magnetic fluid speaker according to claim 3, 5
wherein a radiator is arranged on the front housing.

5. The magnetic fluid speaker according to claim 1,
wherein a storage battery is arranged in the accommodating cavity, and the storage battery is electrically connected to the control panel. 10

6. The magnetic fluid speaker according to claim 1,
wherein the control panel is connected to a button panel, and
the button panel is exposed on the housing.

7. The magnetic fluid speaker according to claim 1,
wherein the magnetic fluid display device comprises a 15
transparent box body and a magnetic fluid enclosed in the transparent box body.

8. The magnetic fluid speaker according to claim 7,
wherein the transparent box body is made of glass or plastic.

9. The magnetic fluid speaker according to claim 7, 20
wherein the transparent box body has a disc-shaped structure.

10. The magnetic fluid speaker according to claim 7,
wherein the housing has a rectangular structure.
